UNITED STATES PATENT OFFICE.

MICHAEL LIPTAK, OF ST. PAUL, MINNESOTA, ASSIGNOR TO A. P. GREEN FIRE BRICK COMPANY, OF MEXICO, MISSOURI, A CORPORATION OF MISSOURI.

FURNACE WALL.

Application filed December 10, 1921. Serial No. 521,377.

To all whom it may concern:

Be it known that I, MICHAEL LIPTAK, a citizen of the United States, residing at St. Paul, in the county of Ramsey and State of Minnesota, have invented certain new and useful Improvements in Furnace Walls; and I do hereby declare the following to be a full, clear, and exact description of the invention, such as will enable others skilled in the art to which it appertains to make and use the same.

My present invention relates to the construction of furnace walls and is in the nature of an improvement on or addition to the construction disclosed and more broadly claimed in my companion application Serial No. 521,376 filed of even date herewith, whereby the wall is adapted to be used in connection with buckstays and, hence, especially adapted for use in boiler installations. In my said earlier application, the complete wall structure is made up of a permanent outer masonry wall and a replaceable inner masonry wall and, as a distinctive feature, the inner wall includes horizontally aligned shelf-forming tiles, certain of which are partly imbedded in and anchored to the permanent outer wall.

The present invention, among other things, provides, as an important feature, metallic anchoring rods detachably interlocked to the partly imbedded shelf-forming tiles and certain of which rods extend outward through and are anchored to the buckstays while other of such rods detachably but positively anchor such tiles to other tiles or bricks of the outer wall structure.

In the accompanying drawings, which illustrate the present invention, like characters indicate like parts throughout the several views.

Referring to the drawings:

Fig. 1 is a fragmentary perspective, with some parts removed, showing a furnace wall designed in accordance with my present invention;

Fig. 2 is a fragmentary plan view of the wall shown in Fig. 1, some of the tiles of the outer wall and shelf-forming tiles of the inner wall being removed;

Fig. 3 is a fragmentary elevation looking at the inner face of the complete wall structure;

Fig. 4 is a vertical section on the line 4—4 of Fig. 2;

Fig. 5 is a fragmentary elevation looking at the outer face of the wall;

Fig. 6 is a fragmentary enlarged section on the line 6—6 of Fig. 2;

Fig. 7 is a fragmentary enlarged section on the same line as Fig. 4;

Fig. 8 is a fragmentary section on the line 8—8 of Fig. 7;

Fig. 9 is a fragmentary plan view illustrating the manner in which certain of the anchoring rods may be applied in working position;

Fig. 10 is a perspective of one of the anchoring rods;

Fig. 11 is a perspective of one of the main shelf-forming tiles;

Fig. 12 is a perspective of one of the supplemental shelf-forming tiles;

Fig. 13 is a perspective showing one of the permanent tiles of the outer wall structure;

Fig. 14 is a view corresponding to Fig. 7 but illustrating a slightly modified construction;

Fig. 15 is a view corresponding to Fig. 4, but illustrating a different kind of anchoring rod applied in working position; and

Figs. 16, 17 and 18 are views corresponding, respectively, to Figs. 11, 12 and 13, but illustrate a slightly modified construction.

The outer or permanent masonry wall is made up chiefly of ordinary bricks 10 laid in mortar in the customary way, but to provide for the shelves to support the horizontal sections of the replaceable inner or fire wall proper, said outer masonry wall is provided, on certain horizontal lines, with tile courses made up preferably of fire tiles 11, 12 and 13. The tiles 12 are the full width of the masonry wall 10. The tiles 11 are the main shelf-forming and supporting tiles of the replaceable inner wall and they are partly imbedded in the outer masonry wall 10 but project so that they will be flush with the inner surface of the replaceable inner wall.

The tiles 13 are located between the tiles 12, aligned with the imbedded ends of the tiles 11 so that the said tiles 11, 12 and 13, when assembled, form a complete layer in the outer wall, with the tiles 11, as indicated, projecting for the purpose stated.

To adapt the anchored shelf tiles 11 to support the supplemental shelf tiles 14, said tiles 11, at their parallel edges, are rabbeted at 15 and the edges of the supplemental tiles 14 are reversely rabbeted so that the latter

105

100

110

will be supported by and horizontally flush with the former.

The main body portion of the replaceable inner wall is made up of high temperature 5 or fire bricks 16 laid in super-imposed horizontal courses on the shelf-forming tiles, filling in the spaces between the vertically spaced horizontal shelves, as best shown in Fig. 1.

10 From the above, it is evident that the complete furnace wall, including what is herein particularly designated as the permanent outer masonry wall and the replaceable inner fire wall, may be made up entirely of 15 masonry work.

When any portion of the inner fire wall has been burned away to a point where it requires replacement, the defective fire bricks or tiles may be removed and replaced 20 without disturbing or taking down the permanent outer wall. If only a few of the bricks 16 have been burned away, they may be removed and replaced without disturbing the shelf tiles. However, usually also some 25 of the shelf tiles will be burned and require replacement and this may be done as follows: Obviously, the replacement of one of the supplemental shelf tiles 14 is a very simple matter since it does not extend into 30 the outer wall. If one of the partly imbedded main shelf tiles 11 requires replacement, it may be easily pulled or knocked out of position, thereby making possible the replacement thereof by a new tile of the 35 same character.

The buckstays illustrated in the drawings are of common construction, being each made up of a pair of vertical channel beams 17 spaced by washers 18 and rigidly connected by rivets 19. For positively anchoring the main shelf-forming tiles 11 in the permanent outer wall, I provide anchoring rods 20, which, as shown in the construction 40 illustrated in Figs. 1 to 14, inclusive, are alike except that the rods 20 are longer than the rods 21. Both classes of rods are threaded at their outer ends and at their other ends are bent to form lock lugs or shoulders 22.

50 The tiles 13, which are permanently built into the masonry outer wall, and the imbedded inner end portions of the main shelf-forming tiles 11 are provided, respectively, with coincident grooves 23 and 24 that are wide enough to pass the lugs 22 when turned 55 horizontally, as shown in Fig. 9, for example. The grooves 23, at their inner extremities, are provided with lock depressions or pockets 25 with which the lugs 22 may be engaged when the anchor rods 20 and 21 are properly turned to accomplish that result; and obviously, when these lugs 60 are thus engaged with said lock depressions, the lock rods will be positively locked to the co-operating main shelf-forming tiles 11.

65 The projecting ends of the long anchor

rods 20 are passed between the beams of the aligned buckstays and, on the outer sides of the latter, are provided with nuts 26, which, when tightened against washers 26^a, not only positively lock the main shelf-forming tiles 11 in the outer wall but positively secure the complete wall structure to the buckstays. The shorter anchor rods 21 are provided at their threaded ends with nuts 27, which, when tightened against washers 27^a, force the latter against the adjacent tiles 13 and positively lock the co-operating shelf-forming tiles 11 to the outer wall structure.

70 With the arrangement described, it is evident that the main shelf-forming tiles will normally be securely anchored or held in the masonry of the main or permanent outer wall. However, when replacements of said tiles 11 are to be made, the nuts of the anchor rods being first loosened, said anchor rods 75 may be rotated ninety degrees, thereby moving the lock lugs 22 thereof into horizontal positions out of the lock depressions 25 and into alignment with the grooves 23 and 24, as shown in Fig. 9.

80 This will release the tiles 11 so that they may be readily displaced or removed from the masonry of the outer or permanent wall 85 and replaced by new tile of the same character.

85 Then, as is evident, the new or substituted tiles may be locked by replacing the anchor rods. The described arrangement also makes it an easy matter to quickly anchor the wall structure to the buckstays.

90 In the somewhat modified arrangement 95 illustrated in Figs. 14 to 18, inclusive, the main shelf-forming tiles 11 are formed in their upper faces with grooves 28, which, at their intermediate portions, have lock 100 depressions or pockets 29. Also, in this arrangement, the permanent wall tiles 13 are formed with grooves 30 that do not extend to the outer ends thereof but terminate in lock depressions or pockets 31. For use in 105 connection with these grooves and pockets, just described, at places where the tiles 11 are not to be anchored to buckstays, I provide anchor rods 32, which, at opposite ends, 110 have downturned ends or lock lugs 32^a that are so spaced that they will drop into the lock depressions 29 and 30 under the action 115 of gravity when said anchor rods are positioned for such engagement.

120 Here it should be noted that the grooves 28 extend toward the interior of the furnace beyond the lock depressions 29 far enough to permit the anchor rods 32 to be positioned therein inward of said depressions 29. In 125 making a replacement of the shelf tile 11, while the fire bricks are removed from above the same, the new tiles are placed in working position, as shown in Fig. 15, the anchor rods 32 are placed in the inner extremities 130 of the grooves 28 with their lugs 32^a hori-

zontally extended, and then said anchor rods are forced toward the outer face of the wall until their lugs 32 come into alignment with the lock depressions 29 and 31, and 5 thereupon said rods will rotate under the action of gravity until their lock lugs 32^a are turned downward into said lock depressions 29 and 31.

In removing a partly destroyed or burned 10 tile 11, it will be necessary to chisel the same away until the inner lock lug 32^a can be reached by a sharp instrument and turned upward into a horizontal position, thereby permitting said rod to be withdrawn toward the interior of the furnace and out of 15 working position. This will release the remaining portion of the defaced tile 11 so that the same may be easily withdrawn from the permanent wall structure.

20 Fig. 14 shows the manner in which the nut-equipped anchor rods 20 can be used in connection with the tile 11 and 13 when provided with the grooves and lock depressions shown in Figs. 14 to 18, inclusive, to 25 anchor the wall to the buckstays.

What I claim is:

1. A wall structure comprising a permanent masonry outer wall, and a replaceable

masonry inner wall, said inner wall having shelf-forming tiles extended from said inner wall into said outer wall and detachably anchored therein, buckstays at the exterior of said wall structure, and metallic anchors interlocked to said shelf-forming tiles and extended therefrom through said outer wall and anchored to said buckstays.

2. A wall structure comprising a permanent masonry outer wall and a replaceable masonry inner wall, said inner wall comprising replaceable shelf-forming tiles independently supporting different belts of the masonry of said inner wall and extended therefrom into said outer wall and detachably anchored therein, said shelf-forming tiles having lock depressions and entrance 45 grooves leading thereto, buckstays at the exterior of said wall structure, and anchoring rods having lock lugs at their inner ends insertable through said entrance grooves and into inter-locking engagement with the lock depressions of said shelf-forming tiles, the outer ends of said rods being threaded and provided with nuts whereby they are detachably anchored to said buckstays.

In testimony whereof I affix my signature.
MICHAEL LIPTAK.
